DESIGN FOR AN AUTOMOTIVE VEHICLE

Norman Bel Geddes and Worthen Paxton, New York, and William H. Stangle, Brooklyn, N. Y.; said Paxton and said Stangle assignors to said Geddes

Application October 28, 1933, Serial No. 49,590

Term of patent 14 years

To whom it may concern:

Be it known that we, NORMAN BEL GEDDES and WORTHEN PAXTON, being citizens of the United States and residing in the Borough of Manhattan, city, county, and State of New York, and WILLIAM H. STANGLE, a citizen of the United States, residing in Brooklyn, New York, have invented a certain new, original, and ornamental Design for Automotive Vehicles, of which the following is a specification, reference being had to the accompanying drawing, forming a part thereof, in which—

Figure 1 is a side elevation of an automotive vehicle embodying our design;

Fig. 2 is a front elevation thereof;

Fig. 3 is a rear elevation thereof; and

Fig. 4 is a perspective view thereof.

We claim:

The ornamental design for an automotive vehicle, substantially as shown.

Signed this 25 day of October, 1933.

NORMAN BEL GEDDES.

WORTHEN PAXTON.

WILLIAM H. STANGLE.
